UNITED STATES PATENT OFFICE.

CHRISTIAN H. SMITH, OF TRANGER, PENNSYLVANIA.

LATCH FOR MINE-CAR DOORS.

No. 874,872.

Specification of Letters Patent.

Patented Dec. 24, 1907.

Application filed August 27, 1907. Serial No. 390,323.

To all whom it may concern:

Be it known that I, CHRISTIAN H. SMITH, a citizen of the United States, residing at Tranger, in the county of Westmoreland and 5 State of Pennsylvania, have invented a new and useful Latch for Mine-Car Doors, of which the following is a specification.

This invention relates to a latch for application to a swinging door depending from 10 horizontal pivot hinges such as are used in mine-cars.

The object of the invention is to provide a simple, durable and useful latch for mine-car doors, one which will not be easily broken 15 and is absolutely reliable under all conditions of operation.

With this and other objects in view the invention consists in certain novel construction, combination and arrangement of parts 20 hereinafter described and definitely claimed.

In the accompanying drawing:—Figure 1 is a rear elevation of a mine-car with the improved latch in closed position thereon. Fig. 2 is a longitudinal sectional view of the rear 25 end of the car on the line 2—2 of Fig. 1 with the latch mechanism in open position.

Similar numerals of reference are used for the same parts in all the figures.

The car, indicated by 1, is mounted as 30 usual on wheels 2 and has one of its ends closed by a dumping door 3 of ordinary construction, but here shown as having a cross bar 4 attached by loop-straps 5 to its upper edge, the ends of which bar project beyond 35 the door and rest in bearings 6 in the sides of the car. The door may swing by its straps on the cross-bar 4, or in the bearings 6, the cross-bar in the latter case being attached to the door. The straps 5 extend on each side 40 of the door nearly to the bottom, and by means of rivets hold the several horizontal boards forming the door in position.

The latch consists in part of a round bar 7, straight except at its lower end where it is 45 bent laterally and reduced in size to form a tapered finger 8. The bar 7 is mounted at an angle to the vertical on the outer side of the door in bearings 9 and 10 near each end of said bar to bring the latter close to the 50 outer face of the door. A notch 11 is made in the under side of the door to permit the finger 8 to turn inwardly under the door 3.

Welded or otherwise secured to the upper 55 end of the latch bar are two projecting arms 12, parallel to each other and extending in a direction opposite to that of the finger 8.

Between the arms 12 is pivoted a hand lever 13, by means of which, the latch bar 7, is turned. The lever is substantially straight, but has a hand grip formed on its outer end 60 and engages, when the latch bar is in locked position, with the keeper 14 attached to the door.

Attached to the floor of the car 1 is a stop plate 15 having its outer end 16 curved upward slightly upon itself and the edge 17 of the upturned portion inclined downwardly away from the latch bar. By this construction the corner nearest the latch bar is the highest point of the stop. The weight of the 70 latch bar and lever is sufficient to keep it in its lowest position, but to prevent it from sliding down too far, the projecting arms 12 are attached to the latch bar in position to rest on the upper bearing 9. 75

When the mine-car door is closed and fastened the hand lever 13 will be held by the keeper 14 and the finger will be across or within the curved stop 16. No pressure which can be brought to bear from within 80 the car is capable of swinging the door open.

When the car has reached the place for dumping, the lever 13 is raised out of the keeper and turned outwardly, this movement causing the finger 8 on the lower end 85 of the latch rod 7 to turn inwardly, and by reason of the inclined position of the rod, upwardly. The upward movement of the finger 8 raises it to such a height that when the door opens there will be an overplus of clearance between the floor of the car and the finger. When the lever is moved to open and close the latch, the arms 12, riding on the upper bearing, prevent the latch rod 7 from dropping. If the lever should be thrown up 95 to its highest position it would not go much beyond the perpendicular because of the upper projecting end of the latch rod, against which the lever would strike.

Having described my invention what I 100 claim as new and desire to secure by Letters Patent is:

1. Combined with a door, an inclined latch bar having a laterally projecting tapering finger on its lower end, bearings for said bar, 105 parallel arms on said bar above and in contact with said upper bearing, a lever pivoted between said arms and a keeper on said door for retaining the latch in closed position.

2. Combined with a swinging door, an inclined bar having a laterally projecting tapered finger on its lower end, bearings for 110

- said rod, parallel arms projecting from said rod in an opposite direction to said finger and resting on one of said bearings, a hand lever pivoted between said plates and having a limited upward movement, and a fixed stop plate having a curved end against which said finger bears, the angular position of said bar being such as to cause the finger to rise when it is turned inwardly on its axis.
- 10 3. A latch for mine-car door, comprising an inclined latch bar mounted to turn in bearings on said door having a lateral projection on its lower end a hand lever on its

upper end and a stop plate on the car having its outward end, with which said finger contacts, upwardly curved, the inclination of said lock bar causing said finger to move inwardly and upwardly when said latch is moved to disengage the door. 15

In testimony that I claim the foregoing as 20 my own, I have hereto affixed my signature in the presence of two witnesses.

CHRISTIAN H. SMITH.
